UNITED STATES PATENT OFFICE.

WILLIAM F. CONNELL, OF NEW YORK, N. Y.

INSTEP-SUPPORT.

1,077,871.

Specification of Letters Patent.

Patented Nov. 4, 1913.

Application filed January 21, 1913. Serial No. 743,239.

To all whom it may concern:

Be it known that I, WILLIAM F. CONNELL, a citizen of the United States, and a resident of the borough of Brooklyn, in the 5 county of Kings, city and State of New York, have invented certain new and useful Improvements in Instep-Supports, of which the following is a specification.

The invention relates to supports for the 10 instep arch of the human foot, and its objects are, among others, to provide a more durable and efficient support of this character which may be made of light sheet metal and, at the same time, will possess unusual 15 strength and durability as well as flexibility within the limits desired; to provide such a support with auxiliary means coöoperating therewith whereby a part of the work of yieldingly supporting the instep is done by 20 said means and a part by the main plate and still another part by the two coöperating and co-acting with each other.

The present invention is in the nature of 25 an improvement on the support shown in Letters Patent of the United States, No. 979,930 of December 27, 1910, and is designed to carry forward the principle of construction therein described and shown.

The invention consists in the construction, 30 combination and arrangement of parts hereinafter described and claimed and illustrated in the accompanying drawings.

In the said drawings, Figure 1 is an under side plan view of an instep arch support embodying the improvements; Fig. 2 is a longitudinal section of the same taken on the line 2—2 of Fig. 1, looking in the direction indicated by the arrows.

The main plate A is arched from end to 40 end and from side to side to approximate the arch of the human instep, and is provided with an upturned curved side portion A' approximating the inner side of the said instep arch. A cover C of leather or other 45 suitable non-metallic substance is secured to the upper side of the main plate by means of rivets E. This cover extends beyond the edges of the plate A and side portion A' in the usual manner to protect the foot of the 50 wearer from the metal. If desired, separate rivets or fastening means may be employed to connect the plate and the cover.

The reinforcing spring B is downwardly 55 curved at its medial part, and at its ends B' and B² is formed on an ogee curve so that it first curves upwardly toward the main plate

and then downwardly on a curve of gradually lengthening radius parallel with the curvature of the part of the plate A with which it is in contact. The spring B is 60 located near the middle of the main plate, extends longitudinally thereof from a point near one end to a point near the opposite end and has its middle portion slightly below the plane of the ends of the plate so 65 that it is constantly in contact with the sole of the shoe in which it is worn and will always act to receive the weight of the foot in the first instance.

The longitudinal slots D and D' are located 70 near the ends of the auxiliary spring B and receive the shanks of the rivets E, which are prevented from withdrawing therefrom by their heads which are of greater diameter than the slots. The rivets 75 are normally located intermediate the ends of the slots, so that the spring B and plate A may be flexed in either direction without placing undue torsional strain on the rivets or the spring adjacent to the slots. This 80 permits the adjustment of the spring or the plate, or both, to meet different conditions without disengaging the spring from its fastenings. It also permits the independent movement of the spring and main plate 85 within certain limits while in use. If desired, the ends of the slots may be enlarged so that by moving the spring until the rivet reaches the enlarged end it may be disengaged therefrom and another spring substituted. 90

The peculiar formation of the ends of the spring B is intended to produce an important result, namely, that of providing a maximum contact surface between the said 95 ends and the main plate and, at the same time, preventing the ends from turning away from the plate when the plate and spring are subjected to pressure. This increases the usefulness and durability of the 100 device and prevents it from causing abrasion of the sole of the shoe.

In operation the weight of the wearer is first received by the medial portion of the spring and the ends of the plate, which 105 causes both spring and plate to extend. As the curvature of the spring is on a smaller radius than the curvature of the plate, however, the extension of these two portions will not coördinate, and this is compensated 110 for by the free movement of the spring or plate relative to the other permitted by

the rivet and slot connection. When the plate has been depressed to a certain extent the spring B will be straightened, and the rivets E will reach the ends of their respective slots, and the spring will then act as a strap to check the further extension of the plate and thus prevent it from cracking. With this device a plate of extremely thin, light metal may be used, and all the efficiency which is usually attained by a relatively heavy plate, secured. It will be understood that the spring may be connected with the plate by means of rivets passed snugly through a hole at one end and a slot of the other, and that other changes in detail may be made without departing from the spirit of the invention.

What I claim is:

In a device of the character described, the combination of a metallic plate curved to

approximate the under surface of the instep and extending from side to side thereof, an auxiliary spring secured to the under side of said plate extending longitudinally thereof from a point near one end to a point near the opposite end and curved downwardly so that its medial portion is normally in contact with the surface upon which the support rests, and a connection between the plate and auxiliary spring arranged to permit a sliding movement of the said parts relative to each other. 25 30

Witness my hand this 15th day of January 1913, at the city of New York, in the county and State of New York.

WILLIAM F. CONNELL.
